(57) **CLAIM**

The ornamental design for a vehicle front upper bumper,
shown and described.

DESCRIPTION

FIG. 1 is a front elevational view of a vehicle front upper bumper;

FIG. 2 is a side elevational view of the vehicle front upper bumper (both left and right side views being mirror images);

FIG. 3 is a top plan view of the vehicle front upper bumper;

FIG. 4 is a bottom plan view of the vehicle front upper bumper; and,

FIG. 5 is a rear elevational view of the vehicle front upper bumper.

The vehicle front upper bumper is styled independently of adjacent vehicle panels. To the extent that any feature lines are illustrated, they are intended to illustrate the crest and valley of the feature and are not necessarily sharp bends in the part. Shading is used to illustrate the curvature of the part and not color. Any functional features of the vehicle front upper bumper are not claimed. Views are orthogonal projections rendered from computer aided design data. The various views are not necessarily to scale in order to better illustrate the design.
